UNITED STATES PATENT OFFICE.

WALTER H. HIMES, OF PITTSBURGH, PENNSYLVANIA, ASSIGNOR TO WESTINGHOUSE ELECTRIC & MANUFACTURING COMPANY, A CORPORATION OF PENNSYLVANIA.

SHORT-CIRCUITING DEVICE.

Application filed May 11, 1921. Serial No. 468,703.

To all whom it may concern:

Be it known that I, WALTER H. HIMES, a citizen of the United States, and a resident of Pittsburgh, in the county of Allegheny and State of Pennsylvania, have invented a new and useful Improvement in Short-Circuiting Devices, of which the following is a specification.

My invention relates to short-circuiting devices and it has particular relation to centrifugally operated mechanisms adapted for employment with dynamo-electric machines to effect repulsion operation during the starting period and induction operation during the normal operating period.

It has been observed, in devices of this general character, that the operation of centrifugally actuated weights frequently becomes impaired from various causes which 20 results in non-uniform outward movement thereof, which causes an uneven contact between the short-circuiting elements and the ends of the commutator bars. Furthermore, when the centrifugally actuated device is 25 located adjacent to the commutator end of the rotor member, it seriously interferes with the ventilation of the commutator.

One of the objects of my invention is to provide a device of the character described 30 in which the weights shall be so interconnected as to ensure uniform outward movement thereof under centrifugal action, thus causing the short-circuiting elements to move axially into contact with the commutator bars with uniform pressure. That is to say, the weights are so connected that the movement of each controls the other to cause 35 a movement in unison, even though one of them may move more freely than the other.

Another object of my invention is to so dispose the centrifugally actuated elements as not to interfere with the circulation of air in the vicinity of the commutator.

A further object is to provide a device of the character designated which shall be readily accessible for adjustment and repairs without the necessity of first removing other parts of the machine.

In the accompanying drawings,

Figure 1 is an end view of a centrifugally operated short-circuiting device constructed in accordance with my invention.

Fig. 2 is a fragmentary side elevation of the mechanism illustrated in Fig. 1.

Fig. 3 is a fragmentary view of a contact-

carrying plate illustrating the notches through which the weight-supporting brackets are adapted to project.

Referring to the drawings, 1 indicates a portion of a commutator cylinder mounted upon a suitable spider 2 which is, in turn, carried by a rotor shaft 3. A ring or plate 4, which is concentric to the shaft 3 and spaced therefrom, is mounted for axial movement adjacent to the commutator 1 by 60 means of diametrically opposed studs 5, which are carried by the spider 2 and project into apertures 6 in the ring 4.

The ring 4 is provided with a plurality of spring contact members 7 disposed in 70 spaced relation with respect to each other and adjacent to the periphery thereof for short-circuiting engagement with the ends of the commutator bars. Each of the contact members 7 preferably comprises a plurality of diverging arms 8 terminating in 75 inwardly curved portions 9 which are adapted to yieldably engage the ends of the commutator bars with a wiping action, as will be hereinafter set forth.

A plurality of brackets 10, each of which comprises a base plate 11 and outwardly extending parallel ear portions 12, are suitably secured to the spider 2 at diametrically opposed points and they project outwardly 80 from the spider between the shaft 3 and the plate 4 through notches 13 formed therein. (Fig. 3.) A plurality of centrifugally actuated elements, each comprising parallel levers 14 having a weight 15 disposed between the outer ends thereof and an anti-friction roller 16 mounted between the inner extremities, are pivotally mounted between the ears 12 of the brackets 10 by means of pins 17.

A pair of helical springs 18 are disposed on each side of the shaft 3, the respective ends of each being connected to the outer or weight end of one of the levers, as at 19, and to the inner or roller end of the 100 diametrically opposed lever, as at 20. (Fig. 2.) By reason of this arrangement, neither lever may move without throwing the other lever out of equilibrium. Thus, any movement of one lever has the effect of actuating 105 the other also, thereby assuring simultaneous action of both weights.

The periphery of the plate 4 is provided with a curved flange 21 which is adapted to coact with the rollers 16 to limit the out- 110

ward movement thereof and to reinforce the plate. The weights 15 are normally maintained in an innermost position and the contact members 7 out of contact with the ends of the commutator bars by means of diametrically disposed compression springs 22 which surround the studs 5 and are disposed between the commutator spider 2 and the inner face of the plate 4 and tend to exert pressure in an outward direction against the plate 4, which, in turn, tends to move the weights 15 inwardly about their pivots 17.

When the machine attains a predetermined speed, centrifugal action will cause the weights 15 to move outwardly against the yieldable pressure of the springs 18 and 22 and to move the antifriction rollers 16 inwardly, thereby causing the plate 4 to move axially toward the commutator, bringing the contact members 7 into contact with the ends of the commutator bars, thereby short-circuiting the same.

The pressure thus brought to bear upon the spring contact members 7 causes the arms 8 thereof to expand, thus exerting a sliding or wiping action against the ends of the commutator bars. This sliding action tends to remove any foreign matter that may have accumulated adjacent to the point of contact and insures an efficient electrical connection.

It will be observed that the plate 4 is in the form of a ring and is so spaced from the rotor shaft 3 that ample space is allowed between the inner circumference thereof and the shaft 3, thus permitting a free and unobstructed circulation of air adjacent to the commutator and precluding the possibility of the formation of dead air spaces.

It will be further observed from the foregoing that a vital feature of my invention resides in the ability to obtain different performances of the device by varying the point at which the springs 18 are attached to the levers 14. Thus, if the point of attachment 19 of the springs 18 to the outer end of the lever 14 is only slightly farther from the pivot 17 of the lever than the inner point of attachment 20, the forces of the two springs will be nearly balanced, and very slight centrifugal force actuates the levers. However, if the outer point 19 is several times as far removed from the pivot 17 as the point 20, a comparatively high speed must be attained before action can occur.

Also, it is considered desirable in the art that, once the movement starts, it shall proceed with increasing force and that it shall be impossible for the weights to move part way and pause or slow down. Such motion would be disastrous in a heavily loaded machine. In such event, the weights might move outward without enough momentum to ensure good electrical contact. This

would cause injury to the contact members.

It is for this reason that the outer point 19 is located on a radius through the pivot which is at right angles to the axis of the spring. Thus, any movement of the weights will swing the spring closer to the pivotal point and reduce the effective resisting moment of the spring. With the spring resistance decreasing and the centrifugal action increasing by reason of the greater radius of the weights, the action is certain to have an accelerating characteristic.

The electrical contact will always be positive and independent of the rate at which the armature accelerates. If more sudden action is desired, the outer point may be carried to some such position as 23 or beyond the right-angle radius which will cause a more gradual decrease in spring torque with a given movement.

Care must be taken to so locate the inner point 20 that, when the weights have reached the outer position, the torque at the inner end does not exceed that at the outer end for the device will be powerless to return itself to its normal position upon the deceleration of the motor.

I claim as my invention:

1. A short-circuiting device comprising a ring-member movably supported adjacent the end of a commutator cylinder and in spaced relation with respect thereto and to the shaft of a dynamo-electric machine, contact members carried by said ring-member for engagement with said cylinder, yieldable means for normally maintaining said contact members out of engagement with said cylinder, and mechanism comprising a plurality of centrifugally actuated means spaced entirely away from the shaft for moving said contact members into engagement with said cylinder when a predetermined speed is attained.

2. In a dynamo-electric machine, the combination with a spider and a commutator cylinder mounted thereon, of a short-circuiting device comprising a plurality of supporting pins extending longitudinally from the end of said spider, and an annular plate movably mounted on said supporting pins and in spaced relation with respect to said cylinder and with respect to the shaft of a dynamo-electric machine.

3. A short-circuiting device comprising a plate movably supported adjacent to a commutator cylinder and in spaced relation thereto, and with the shaft of a dynamo-electric machine to admit of the unobstructed circulation of air adjacent to said cylinder, a plurality of spring contact members carried by said plate for engagement with said commutator cylinder, means for maintaining said contact members out of engagement with said cylinder, a plurality of substantially diametrically opposed

levers pivotally mounted adjacent said plate, each of said levers being provided with centrifugally actuated weights at one end and an antifriction roller at the other 5 end thereof for engagement with said plate to so move said plate as to cause said contact members to engage said commutator cylinder, and a plurality of springs so connecting the outer extremities of each of 10 said levers to the inner extremities of the diametrically opposed levers as to cause said levers to operate in unison.

4. The combination with a rotor member, of a switch comprising contact elements 15 carried by said rotor member, an axially movable ring-member adapted to make contact with said contact elements, axially disposed yielding means for forcing said ring-member away from said contact elements, 20 a pair of oppositely disposed, substantially longitudinally extending lever members engaging said ring-member at their inner ends and carrying weights at their outer ends, means carried by said rotor member 25 for pivotally supporting said lever members, and a link member connecting a point on the inner end of one lever member to a point on the outer end of the other lever member.

30 5. The combination with the rotor member of a dynamo-electric machine, of a winding thereon and means for short-circuiting a plurality of portions of said winding, said means comprising contact elements 35 carried by said rotor member and electrically connected to said winding portions, an axially movable ring-member adapted to make contact with said contact elements, a pair of oppositely disposed, 40 substantially longitudinally extending lever members engaging said ring-member at their inner ends and carrying weights at their outer ends, means carried by said rotor member for pivotally supporting said lever members, and a spring member connecting 45 a point on the inner end of one lever member to a point more remote from the pivot on the outer end of the other lever member.

6. The combination with the rotor member 50 of a dynamo-electric machine, of a winding thereon and means for short-circuiting a plurality of portions of said winding, said means comprising contact elements carried by said rotor member and electrically connected to said winding portions, an axially movable ring-member adapted to 55 make contact with said contact elements, a pair of oppositely disposed, substantially longitudinally extending lever members engaging said ring-member at their inner ends 60 and carrying weights at their outer ends, means carried by said rotor member for pivotally supporting said lever members, and a pair of crossed spring members, each 65 spring member connecting a point on the

inner end of one lever member to a point more remote from the pivot on the outer end of the other lever member.

7. The combination with a rotor member, 70 of a switch comprising contact elements carried by said rotor member, an axially movable ring-member carrying resilient contact fingers adapted to make contact with said contact elements, axially disposed spring means for forcing said ring member away 75 from said contact elements, a plurality of spaced lever members lying substantially in radial axial planes, the ends of said lever members adjacent said rotor winding being 80 in operative engagement with said ring-member to press the same into engagement with said contact elements, the opposite ends of said lever members being weighted, and means for pivotally supporting said lever members intermediate their ends with their 85 ring-member ends farther from the shaft than their pivots when the shaft is stationary and being movable to points substantially the same distance from the shaft as 90 said pivots.

8. The combination with a commutating cylinder, a supporting spider therefor, a shaft for said spider, a movable ring providing a ventilating opening near said shaft and carrying contact fingers adapted to 95 operate electrically with said commutating cylinder, a supporting member extending from the end of said spider through said ring in spaced relation to said shaft, and centrifugal means mounted on said supporting member in operative relation to said ring for controlling its movement.

9. The combination with a commutating cylinder, a supporting spider therefor, a shaft for said spider, a movable ring providing a ventilating opening near said shaft and carrying contact fingers adapted to 105 operate electrically with said commutating cylinder, means for providing a supporting member spaced axially outwardly from said ring while providing also for said axial ventilating opening, and centrifugal means mounted on said supporting member in operative relation to said ring for controlling 110 its movement.

10. The combination with the rotor member of a dynamo-electric machine, of a winding thereon and means for short-circuiting a plurality of portions of said winding, said means comprising contact elements carried 120 by said rotor member and electrically connected to said winding portions, a shaft for said rotor member, a movable ring adapted to make contact with said contact elements and providing a ventilating opening near said shaft, means for providing a supporting member spaced axially outwardly from said ring while providing also for said axial 125 ventilating opening, and centrifugal means supported by said supporting member in 130

operative relation to said ring for controlling its movement.

11. A speed-responsive device comprising a shaft, an axially movable ring-member, a plurality of spaced lever members lying substantially in radial axial planes, the ends of said lever members adjacent said ring-member being in operative engagement therewith, the opposite ends of said lever members being weighted, means for pivotally supporting said lever members intermediate their ends with their ring-member ends at substantially the same distance from the shaft as their pivots when said lever members are moved to their operative positions by centrifugal force, and axially disposed spring means associated with said ring-member for opposing the centrifugal movement of said weights.
12. The combination with a rotor member, of a switch comprising contact elements carried by said rotor member, a shaft for said rotor member, a movable ring carrying resilient contact fingers adapted to make contact with said contact elements, axially disposed spring means for forcing said mov-

able ring in an axial direction away from said contact elements, means for providing a pair of oppositely disposed supporting pivots spaced axially outwardly from said ring and radially outwardly from said shaft, a pair of substantially longitudinally extending lever members operatively associated with said ring at their longitudinally inner ends and carrying weights at their longitudinally outer ends, said lever members being pivoted at intermediate points on said pivots, respectively, and a pair of crossed spring members, each spring member connecting a point on the inner end of one lever member to a point more remote from the pivot on the outer end of the other lever member, whereby said spring members produce a resultant resisting moment opposing the centrifugal movement of the weights, the points of application of the spring members being so chosen that said resisting moment is decreased as the weights move outwardly.

In testimony whereof, I have hereunto subscribed my name this 3rd day of May 1921.

WALTER H. HIMES.
